UNITED STATES PATENT OFFICE.

MARCUS FINKELSTEIN, OF NEW YORK, N. Y.

COLLAR AND STIFFENER THEREFOR

1,233,860.

Specification of Letters Patent. Patented July 17, 1917.

Application filed September 25, 1916. Serial No. 121,983.

To all whom it may concern:

Be it known that I, MARCUS FINKELSTEIN, a citizen of the United States, and a resident of the city of New York, borough of Manhattan, in the county and State of New York, have invented a new and Improved Collar and Stiffener Therefor, of which the following is a full, clear, and exact description.

- 10 The invention relates to soft shirt collars and its object is to provide a new and improved collar and stiffener therefor arranged to stiffen the neckband with a view to maintain the shape of the turndown portion and 15 to prevent it from wrinkling and to hold the neckband more or less out of contact with the neck of the wearer to prevent perspiration from wilting the collar especially the turndown portion thereof. Another 20 object is to permit of conveniently removing the stiffener from a worn or a soiled collar and applying it to a fresh collar while the worn or soiled collar undergoes the usual washing and laundrying. A further object 25 is to make the turndown portion detachable from the neckband to permit the soiled turndown portion of the collar to be detached from the neck band for independent washing and laundrying.
- 30 In order to accomplish the desired result the neckband of a collar is provided with a pocket or recess for removably holding a flexible stiffener or shaper.

A practical embodiment of the invention 35 is represented in the accompanying drawings forming a part of this specification, in which similar characters of reference indicate corresponding parts in all the views.

Figure 1 is a plan view of a soft turndown collar with the parts in extended position;

Fig. 2 is a cross section of the soft turndown collar on the line 2-2 of Fig. 1, the flap being turned down;

45 Fig. 3 is a plan view of the stiffener or shaper.

The soft shirt collar in its general construction consists of a neckband 10, a turndown portion 11 and a stiffener or shaper 12 50 removably held in a pocket 13 formed in the neckband 10. The turndown portion 11 of the collar is detachably connected to the neckband 10 by fasteners 14 such as press buttons of the stud and socket type, as 55 shown. By making the turndown portion 11 detachable from the neckband 10 the turn-

down portion when soiled can be readily removed from the neckband and replaced by a fresh one.

The neckband 10 is made of several layers or plies and the outermost layer is spaced from the next following one so as to provide the pocket 13 for the reception of the stiffener or shaper 12. This pocket 13 is closed at the top, bottom and at one end by 60 stitches which connect the plies with each other, but is open at the other end 16 to permit of conveniently inserting the stiffener in the pocket 13 or removing it therefrom.

The stiffener or shaper 12 is preferably in the form of a skeleton frame made of celluloid, sheet metal or other suitable material capable of flexing to conform to the shape of the neckband when the collar is used on the shirt. The stiffener or shaper 12 conforms approximately to the shape of the 70 neckband, that is, its upper margin extends close to the upper margin of the neckband while the ends are converging downwardly and inwardly. By reference to the drawings, it will be noticed that the pocket or 75 recess 13 terminates at the inner ends of the usual buttonhole flaps 20 and 21 of the neckband so that the collar can be readily fastened in position on the neckband of the shirt.

It will be noticed that the neckband 10 is 80 kept stiff, the turndown portion 11 hangs down properly from the stiffened neckband and is hence not liable to wrinkle and as a consequence keeps its shape as long as the 85 collar is used. By making the stiffener or shaper 12 of a thin, light flexible material it does not exert any pressure on the neck of the wearer and it does not materially detract from the flexibility of the neckband 95 itself.

It will further be noticed that by stiffening the neckband the latter is held more or less out of contact with the neck of the wearer, and even if the neckband becomes 100 saturated with perspiration the latter is not liable to penetrate to the turndown portion 11, and hence the latter maintains its shape and appearance. By making the turndown portion 11 detachable from the neckband 10 the user is enabled to change the turndown portion 11 twice or even more times a day 105 without even removing the neckband from its position on the shirt.

It will further be noticed that the detachable turndown portion 11 may be made of

a different material than the neckband and also its shape can be varied to suit the taste of the wearer without requiring any change in the neckband itself.

5 Having thus described my invention, I claim as new and desire to secure by Letters Patent:

1. A soft turndown collar having a neckband provided with a pocket, a turndown portion detachably connected with the said

neckband, and a stiffener held removably within the pocket of the neckband.

2. A soft turndown collar having a neckband provided with a pocket, a stiffener in the pocket, a turndown portion, and fasteners detachably securing the turndown portion to the inner face of the upper edge of the neckband. 15

MARCUS FINKELSTEIN.
